J. J. MORROW

AUTOMATIC ROLLER FASTENER

Filed June 9, 1924

FIG. 1 -

Patented June 2, 1925.

1,539,858

UNITED STATES PATENT OFFICE.

JOHN J. MORROW, OF NEW YORK, N. Y., ASSIGNOR TO A. C. WICKE MANUFACTURING COMPANY, OF NEW YORK, N. Y., A CORPORATION OF NEW YORK.

AUTOMATIC ROLLER FASTENER.

Application filed June 9, 1924. Serial No. 718,737.

To all whom it may concern:

Be it known that I, JOHN J. MORROW, a citizen of the United States, and a resident of 619 West 176th Street, in the city, county, 5 and State of New York, have invented a new and useful Improvement in Automatic Roller Fasteners, of which the following is a specification.

This invention relates to fastening devices 10 for doors and more particularly to automatic roller fasteners for refrigerator doors and the like.

An object of my invention is to provide 15 a fastening device for doors which is of simple construction, easy to manipulate from either side of the door, and inexpensive to manufacture.

Another object of my invention is to provide 20 a fastening device for refrigerator doors in which the spring for automatically operating the latch is hidden.

Another object of my invention is to provide 25 a fastening device for refrigerator or other doors which is capable of manual operation from either side of the door and which has the manual means for opening the latch disposed substantially adjacent the free edge of the door.

A further object of my invention is to 30 provide a fastening device for refrigerator doors and the like which includes an operating lever for opening the door from the outside and means for opening the door from the inside which is not connected to the outside operating lever.

Other objects of my invention will be apparent from a reading of the following description.

Certain forms of automatic roller latches 40 which have been quite extensively manufactured, are provided with torsion springs. These springs are disposed around the shaft carrying the latch arm, and positioned intermediate the latch arm and the lever for 45 operating the latch from the outer side of the door. By reason of the location of the spring upon the shaft, the operating lever is necessarily placed at some distance from the edge of the door, as the springs are of 50 considerable length, thus reducing the amount of available leverage for opening and closing the door.

Inasmuch as refrigerator doors of the type employed in meat markets and packing 55 houses and the like, are of considerable

weight, it is desirable to swing the door open with the least amount of effort, and, obviously, if the lever is disposed at the edge of the door one would secure the greatest amount of leverage to accomplish this operation. In order to obtain this desirable advantage, my invention provides for locating the operating lever substantially at the edge of the door. I am able to obtain 60 this advantage by reason of the fact that the torsion spring is dispensed with and in its stead I employ a compression spring which is located within the door.

By placing the spring within the door I also overcome the objection to the exposed 70 torsion springs which is that of collecting dust, grease, and the like, thus making the latching mechanism of unsanitary appearance. In addition, torsional springs are subject to breakage which necessitates their 75 replacement, during which time the latching means are temporarily rendered inoperative.

In order to overcome the above disadvantages, my invention provides for placing 80 the spring within the door, and it is so arranged that it may directly cooperate with the usual plunger rod which is employed to release the latching means from within the door. This change in location of the 85 spring enables me to provide for a different action thereof, as the spring may operate through its expansive action to retain the latching roller in its normal locking position. Obviously, with compressive springs, 90 the breakage of the spring between its ends does not render the latching means inoperative, because the spring may still be compressed, while with the torsion spring, if the spring were to break, its entire effectiveness 95 to throw the latching roller would be destroyed. The change in location of the spring enables me to position the outer operating lever for releasing the roller latch as close to the edge of the door as is desirable and thus provide for the easy opening 100 of the door thereby. In addition, the spring is removed from a position where it can gather moisture, dust, grease and the like, and thus maintains the latch in a sanitary 105 condition.

The invention may be better understood by referring to the following description and the drawing, in which—

Fig. 1 is a plan view of the improved 110

latching device with the outer end of the outside operating lever broken away.

Fig. 2 is a front view of the latching device with a portion of the outer operating lever removed, and

Fig. 3 is a view showing the latching mechanism together with the plunger rod and spring for operating the latch from the inner side of the door and normally holding the latching roller in locking position, the view being taken on line II—II, Fig. 2.

Fig. 4 is a modified form of the connection between the plunger rod and the arm for operating the latching roller.

In the embodiment of my invention illustrated in the drawing, the latching device comprises a supporting plate 4 from which project bearings 5 in which a shaft 7 is journalled to rotate freely therein. One end of the shaft is disposed adjacent to the edge of the door and is provided with a rigid arm 8 extending at right angles therefrom. The end of the arm is provided with a roller 9, which is adapted to engage a keeper 11 integral with a foot plate 12 which may be fastened to the jamb of the refrigerator in any desirable manner. The keeper 11 has an inclined face 13 which is adapted to force the roller upwardly so as to rock the shaft 7, thus placing a spring, to be described hereinafter, under compression. The keeper has an undercut portion 13' in which the roller snaps after it has ridden over the inclined face 13, thus securing the door firmly in locked engagement with the refrigerator casing or jamb thereof.

In order to open the door from the outer side with the least possible exertion, I provide a lever 14, which has a hub portion 15 pinned at 16 to the shaft 7. As will be noted from Figs. 1 and 2, the lever 14 is located substantially in line with the edge of the door, thus affording the greatest amount of leverage with which to open the same with respect to the pivotal support of the door.

The door may be opened from the inner side by means of a plunger rod 17 which has a knob 18 on its inner end and has its outer end 19 connected to an arm 21 which latter is pinned to the shaft 7 at 22. The connection between the plunger rod 17 and the arm 21 may consist of a cross-pin 23 carried by the end of the rod 17, which pin engages a curved slot or opening 24 in the end of the arm 21. The curvature of the slot 24 is such that the longitudinal movement of the rod is substantially at right angles to a tangent to the curve at the point of contact of the pin with the curve at any point of its movement. The arm 21 may be vertically slotted at 24' to provide for movement of the rod 17.

The plunger rod 17 has an enlarged inner section 25 and a reduced stem 26, thus providing a shoulder 26' against which one end

of a compression spring 27 may abut. The other end of the spring 27 engages the supporting plate 4. It will thus be seen that upon a thrust or endwise movement of the plunger rod 17 toward the face of the door that the spring 27 will be placed under compression and that the end of the plunger rod operating upon the arm 21 will rock the shaft 7 and the arm 8 carrying the roller 9 from its engagement with the keeper 11. Upon releasing the pressure upon the knob 18, the potential energy stored in the spring will rotate the shaft 7 and the arm 8 to its normal locking position, so that when the door is closed the latch will automatically lock the same.

It will be apparent from the foregoing description that by housing the spring within the door, it is removed from a position where it will gather dirt, grease and the like, and also that it functions in a different manner from the springs heretofore in use and which depended upon a torsional action.

In order to prevent the shaft 7 from being moved longitudinally from its bearings 5, a collar 28 may be pinned, as at 29, thereon. The rigid arm 8 prevents an opposite longitudinal movement of the shaft 7.

Although I have described and illustrated the plunger rod as being connected by a pin and slot arrangement to the arm 21, I also contemplate merely an engagement therebetween. In such construction, which is illustrated in Fig. 4, the face of an arm 33 adjacent to the end of a plunger rod 34 may have an arcuate face 35, and the end of the rod 34 may be provided with a roller 36 to facilitate its movement over the curved face of the arm. In such construction, it is essential that means be provided to return the latch to its initial or locking position. This may be readily accomplished by entwining a spring 36' about the shaft 7 and anchoring one end thereto and having the other end extend up on the inner side of the arm 33, or a spring of this or other types may be applied to the lever 14.

In order that there may be no considerable amount of leakage of warm air into the refrigerator through the opening provided for the plunger rod, packings or gaskets 37 and 38 may be provided in frictional engagement with the plunger 17. The application of such insulating packing is obvious to those skilled in the manufacture of refrigerators and the like.

A rubber strip 43 may be disposed between the edge of the door and the jamb to provide for an hermetic seal.

The refrigerator door may be of the usual type consisting of frame members and panels forming the inner and outer faces of the door, and an insulating material 41 may be disposed therebetween.

For the purpose of providing locking means for the present device, the keeper 11 is provided with an aperture 43' through which the bolt of a pad-lock may be passed and locked when the roller 9 is engaged with the keeper. The pad-lock will thus prevent the removal of the roller from the keeper and thus provide an effective lock.

Modifications of my invention will suggest themselves to those skilled in the art, but such as come within the terms of the appended claims are contemplated by me as falling within the spirit of my invention.

What I claim is:

1. A fastener for doors, comprising a latch for holding the door closed, a hand lever disposed adjacent the edge and upon the face of the door for releasing the latch from the outside of the door, a plunger rod extending through the door, a spring within the walls of said door and surrounding a portion of said rod, said plunger rod being associated with said latch so that the spring is placed under compression when the lever is moved to release the latch and to return the latch to locking position.

2. A fastener for doors, comprising a latch for holding the door closed, a shaft disposed parallel to the face of said door, said latch being disposed on one end of said shaft, a lever secured to said shaft for releasing the latch from locking position, an arm secured to said shaft and disposed adjacent said lever, and means within the door associated with said arm for throwing the latch to locking position.

3. A fastener for doors, comprising a latch for holding the door closed, a shaft disposed parallel to the face of said door, said latch being disposed on one end of said shaft, a lever secured to said shaft for releasing the latch from locking position, an arm secured to said shaft and disposed adjacent said lever, a rod extending through the door and associated with said arm for releasing said latch, and means disposed around said arm for normally throwing the latch to locking position.

4. A fastener for doors comprising a latch for holding the door closed, a lever 50 arm on and parallel to the edge of the door and adjacent said latch for releasing the same, an arm adjacent said lever and remote from said latch, and means including a spring for normally throwing the latch 55 to locking position and operable to release the latch from the inner side of the door.

5. A fastener for doors comprising a shaft parallel to the outer face of the door, a latch arm at one end of said shaft, a 60 swinging lever on and parallel to the edge of said door and adjacent said latch, an arm at the other end of said shaft, a plunger rod extending through the door and engaging said arm, and means surrounding said rod 65 for normally throwing the latch to locking position.

6. A fastener for doors comprising a rock shaft, a latch arm extending at right angles from one end of said shaft, a lever secured to said shaft and disposed adjacent the end of the shaft upon which said arm is located, an arm secured to said shaft adjacent said lever, and means within the door for engaging said arm to normally maintain the latch in locking position.

7. A fastener for doors, comprising a shaft adapted to rotate about an axis substantially parallel to the plane of the door, an arm secured to one end of said shaft, a 80 latch roller carried by said arm, a stationary keeper having an inclined front surface adapted to engage the latch roller, a spring normally tending to throw the arm on the shaft so as to hold the latch roller in engagement with the keeper, said spring being disposed in said door, a lever for swinging said latch so as to release the same from the keeper, and a rod extending through the door and associated with said shaft for releasing the latch roller by operation from within the door.

In testimony whereof, I have hereunto subscribed my name this 3 day of June, 1924.

JOHN J. MORROW.
